SIGNAL DEVICE

Gus Kaich, Jacksonville, Tex.

Application July 30, 1932, Serial No. 626,815

2 Claims. (Cl. 177—339)

The present invention is a continuation in part of my application, Serial No. 475,227, filed August 14, 1930, since abandoned and relates to improvements in signal devices, and more particularly to 5 a traffic signal device adaptable to traffic conditions in small towns and villages.

An object of my invention is to provide a traffic signal device having means for augmenting the negative acceleration of vehicular traffic, approaching a road or street intersection.

Another object of my invention is to provide means at a street intersection whereby oncoming traffic will automatically and with greater certainty operate signals to permit crossings in 15 safety.

With these and other objects in view, which may be incident to my improvements, the invention consists in the parts and combinations to be hereinafter set forth and claimed, with the understanding that the several necessary elements, comprising my invention, may be varied in construction, proportions and arrangement, without departing from the spirit and scope of the 20 appended claims.

25 An effective traffic signal of the type designed for the purpose herein described must perform the diversified function of informing operators of vehicular traffic of their approach to an intersection in such a manner as to assure operation

30 of the signal means by which traffic approaching from an angular direction will be given a signal to stop. The performance of this function, is the result of the complementary and cooperating action of the elements of my invention, namely, a 35 sinuously surfaced approach roadway, having at its exit extremity a weight operation signal switch.

In the drawing, like numerals refer to similar parts throughout the several views, of which 40 Figure 1 is a top plan view of a street intersection showing the position of the several sinuously surfaced roadways or traffic lanes approaching a street intersection and the center signal means.

45 Fig. 2 is an end view of the signal mechanism. Fig. 3 shows the detailed structure; and

Fig. 4 is a sectional view of Figure 2 along the line $x-x'$.

Referring to the drawing and particularly to 50 Figure 1 thereof, a highway intersection plan is shown comprising a series of a sinuously surfaced roadways or traffic lanes 1, positioned between a curbing 3 and the street center $y-y'$ along the right half of the street as traffic approaches the 55 intersection. The traffic lane is preferably con-

structed of reenforced concrete as shown in Fig. 2 and extends approximately 125 to 200 feet from the intersection entrance. The lineal edge of the lane is designed with a bevel 4 so that, when expedient traffic may approach the lane at an angle.

The sinuous surface 2 comprises a series of waves 5 which are designed both as to perpendicular height and crest to crest separation to augment the negative acceleration normally accomplished solely by brake action of vehicular traffic approaching a street intersection. By this means the speed of traffic can be effectively yet satisfactorily retarded to a definite slow rate whereby street intersection approaches and crossings can be negotiated with a maximum degree of safety.

This is effectively accomplished by positioning the wave crests sufficiently far apart at the approach end of the sinuated roadway and so fixing the increment of decrease, in the lineal distance between the crests, as to provide positive yet satisfactory means for causing the operator to reduce the speed of the vehicle. Thus when the operator and the vehicle are subjected to a slight undulating or wave motion, the operator will become aware of the necessity for reducing the speed of the vehicle to a safe maximum speed or to a complete stop.

A study of the problem has shown that automobiles with the present wheel base range of from 90 inches to 150 inches traveling at a speed of from 25 to 30 miles per hour, can be brought to a speed of five miles per hour without injury to the car or occupants when driven over a sinuated traffic lane surface having a valley to crest perpendicular height of substantially 4 inches and a crest to crest distance beginning with 12 feet and decreasing one foot thereafter until a 4 foot phase distance is reached.

It will be appreciated that the distance between the wave crests may be varied, resulting in a consequent variation in the number of sinuations or waves and an increase or decrease in severity of brake action and negative acceleration.

The present construction provides positive yet not objectionable perceptiveness to the necessity for speed diminution and consequent safety.

The sinuous traffic lane or roadway surface is gradually sloped as shown at 6, Fig. 1, at the approach end to afford a slight yet positive sense-perception of its presence.

While a weight operated switch of the type herein described may be constructed sufficiently sensitive to be actuated by vehicles traveling at all

speeds, I have selected in order to combine safety and certainty of operation, to substitute a slowing down means for sensitiveness in the switch mechanism, and in this manner solve the two-fold difficulty which the problem presents, namely, informing the vehicle operator that he should stop and assuring the positive operation of the switch.

The signal means 7 is most satisfactorily located at a distance of approximately 10 to 12 feet beyond 10 the final wave crest and approximately 15 to 18 feet back of the pedestrian lane 16, over which space there is a gradual slope to the normal level of the street surface. The signal 7 comprises a U-shaped steel platform 8, slidably mounted in an 15 upright U-shaped trough support 9 provided with L-flanges 10 to permit free vertical reciprocating motion. A pair of heavy steel springs 11, provide a resiliency support means for the platform.

A contact plunger bar 12, projecting downwardly at right angles from the platform 8, engages a U-shaped contact receptacle 13, when it is pressed downwardly by the weight of the vehicle. The circuit 14 is thereby energized, lighting a signal light in the approximately square light 20 dome 15, at right angles to the direction of travel 25 of the vehicle energizing the signal. A time operating device of the well known solenoid slow moving type not shown, may be satisfactorily used, so as to keep the light signal on for a substantial 30 period of time.

It is believed that the complete construction and operation of the device will be clearly understood from the foregoing description. As the vehicle approaches the street intersection, on the right 35 side of the roadway, the sinuously surfaced lane is encountered. The waves or undulations are formed and positioned so as to positively yet satisfactorily augment the necessary speed decrease for negotiating intersecting crossings. At the end 40 of the undulated portion of the traffic lane the ve-

hicle presses downwardly a slidably mounted platform whereby a signal light operates to stop traffic coming at right angles and thus permitting crossing of street intersections in safety.

It will be seen that the general plan as shown 80 in Fig. 1 provides for a sinuous traffic lane and signal operating means on each of the intersecting streets. Each signal operating means energizes a stop light at right angles to the direction of traffic 85 energizing the signal.

This means of regulating traffic at street intersections is especially adaptable where traffic is not of sufficient volume to warrant the use of the well known multiple light system.

While I have shown and described the preferred 90 embodiment of my invention, I wish it to be understood that I do not confine myself to the precise details of construction herein set forth, by way of illustrations, as it is apparent that many changes and variations may be made therein, by those skilled in the art, without departing from the spirit of the invention, or exceeding the scope of the appended claims.

What I claim is:

1. In a vehicular actuated signal system comprising a traffic lane having an entrance and an exit for traffic thereover, said lane having an undulated surface formed by a plurality of vertical undulations and a vehicular operated switch positioned at the exit end of said lane.

2. In a vehicular actuated signal system comprising a traffic lane having an entrance and an exit for traffic thereover, said lane having an undulated surface formed by a plurality of vertical undulations, the undulations being positioned in a regularly diminishing longitudinal space relation to each other, and a vehicular operated switch positioned at the end of said lane.
